PALLET FEEDING DEVICE FOR CONCRETE BLOCK MACHINES

Paul E. Bohm, Sr., South Bend, Ind.

Application June 23, 1948, Serial No. 34,796

14 Claims. (Cl. 214—8.5)

1

This invention relates to a pallet feeding device for concrete block machines. The use of pallets in the manufacture of concrete blocks to support the blocks during the molding thereof and, after molding, during curing or setting thereof has been practiced for many years. These pallets constitute metal plates which are usually inserted into the block molds of a block-making machine by hand, each pallet being removed from the machine with the block molded thereon. Since the pallets must be fed to the block molds between the successive molding operations, the manual application thereof has been time-consuming and has limited the capacity of the output of the block machine. This is particularly true in machines having multiple cavity molds because of the necessity of positioning each pallet in a mold accurately so that it assumes a horizontal position at the bottom of the mold cavity.

The primary object of this invention is to provide a device of simple rugged construction adapted for use in conjunction with a concrete block machine without interfering with the functioning of that machine and which is operable to discharge pallets in operative position in a block mold of the machine.

A further object is to provide a device of this character which includes a support upon which one or more piles of pallets are stacked, a guide below the support, and a feed member which reciprocates on the guide and is operable to release the lowermost pallet of each stack and propel it along the guide for passing into a mold.

A further object is to provide a device of this character with a guide upon which a feed member reciprocates, said guide being characterized by a shiftable section normally held in one position but movable to a discharge position when the feed member reaches a predetermined position thereon.

A further object is to provide a device of this character with a guide member including a plurality of shiftable parts and a primary and secondary track, which guide member is traversed reciprocably by a feed member between two limits of movement, wherein the feed member has a pair of pivoted parts normally traversing said primary track, of which one tilts at the end of one stroke thereof to a pallet discharging position providing for traverse thereof along the secondary track of the guide upon its return stroke.

Other objects will be apparent from the following specification.

2

In the drawings:

Fig. 1 is a view of the device in side elevation.

Fig. 2 is a top plan view of the device with parts broken away.

Fig. 3 is an enlarged fragmentary side view of the guide and feed portions of the device.

Fig. 4 is a fragmentary plan view of a portion of the device illustrated in Fig. 3.

Fig. 5 is a fragmentary end view of the device as seen from the right in Fig. 1.

Fig. 6 is an enlarged fragmentary side view illustrating a portion of the guide.

Fig. 7 is a transverse sectional view taken on line 7—7 of Fig. 6 and illustrating the roller in an axially centered position relative to said section line.

Fig. 8 is a fragmentary view illustrating a roller, its mounting member and related parts, with parts illustrated in axial section.

Fig. 9 is a detail face view of one of the control switches of the device.

This invention is adapted to be used in conjunction with a concrete block machine of the character having stationary molds 10 which serve

25 to outline a concrete block formed therein, which block is lifted from the mold after formation thereof, being supported upon cored pallets 11 which may be engaged by suitable lift means for transfer of the formed block supported upon the pallet from the mold to a rack or other member upon which it may be mounted during the curing or hardening of the block, as from position 10 to position 10' in Fig. 2. The block-forming machine includes a shiftable discharge member

30 for concrete, a pressure member for acting upon the concrete after the mold has been filled, and a vibrator for packing the concrete in the mold. These parts are conventional and are not shown herein. Certain parts of the frame of the machine only are shown for purposes of illustrating

35 the attachment of the device comprising the instant invention thereto. Such parts include the frame elements 12 and 13 which have been illustrated solely for purposes of defining the relationship of the feeding device to the machine, and particularly to the molds 10 of that machine.

40 The instant machine comprises a guide member 20, generally inclined as illustrated in Fig. 1, whose lower end terminates in a position adjacent and above the molds 10 and is fixedly secured to the frame part 12 of the machine as by bolts 21. The opposite end of the guide unit 20 is supported by legs 22 having foot members 23 bearing upon a floor or other supporting surface. The guides include two longitudinal or

3

side members extending in spaced parallel relation suitably interconnected at their opposite ends by cross-members 24. This guide structure will be described in greater detail hereinafter. The supporting legs 22 project above the level of the guide 20, and at one end support the outer ends of longitudinal members 25 whose inner ends are secured by bolts 26 to a stationary part of the frame of the machine, for example, the frame part 13. Uprights 27 are carried by the horizontal members 26 and at their upper ends support upper longitudinal frame members 28 which may be connected at their inner ends to the part 13 of the machine frame. A plurality of rigid angle members 29 are fixedly secured to the longitudinal members 25 and 28 and project below the member 25 to terminate adjacent to the guide unit 20, as best seen in Fig. 1. Intermediate bars 30 may likewise be supported by the members 25 and 28. The assembly of the parts 25 to 30, inclusive, provides a support within which one or more piles of pallets 11 may be stacked in an inclined position with the ends or edges of the pallets adjacent the block-forming machine positioned lowermost. It will be understood that the angles 29 engage the corners of these pallets and retain them in the desired stacked position, and longitudinal bottom members (not shown) support the weight of the stack.

A feed member or unit 31 traverses the guide 20 and is adapted to remove the lowermost pallet of each stack upon each working stroke thereof, carrying the same to a position above the mold 10 where it tilts to an inclined position accommodating the discharge of the pallet 11 into the mold, as illustrated in Fig. 1. For this purpose the angles 29, shown at the left in Fig. 1, terminate above the position of the work-feeding means 31 a distance slightly greater than the thickness of a pallet to permit the sliding of a pallet from the bottom of the stack by said feed member while retaining all pallets above the pallet to be withdrawn, in the stacked position.

The side members of the guide each comprise a wide plate 35 positioned in a vertical plane and being of a greater width at its lower inner end, as illustrated in Figs. 1 and 3, than at its upper outer end, and being characterized by an inclined bottom edge portion 36 intermediate its wide and narrow portions. An angle iron 37 is welded along the inner margin of the narrow portion of each of the plates 35 with its flange 38 projecting inwardly therefrom. A similar angle iron 39 is welded along the lower inclined margin of the plate 35 at the part 36 thereof, said angle iron 39 being inclined at an angle to the angle iron 37 and having its inwardly projecting flange in end abutment with the flange 38 of the angle iron 37. A third angle iron 40 is welded along the margin of the wide part of the plate 35 with its inwardly projecting flange 41 in end abutment with the inwardly projecting flange of the angle iron 39. The inwardly projecting flanges of the angle irons 37, 39 and 40 thus form continuous tracks at the opposite sides of the guides with the tracks of the angle irons 37 and 40 being substantially parallel but extending at an angle to the inwardly projecting flanges of the angle iron 39. The upper margins of the plates 35 preferably include inwardly bent portions 42 and terminate in inwardly offset vertical flange portions 43. The members 30 and the flanges of the angle irons 29 which are parallel to the plates 35 may be welded or otherwise

secured to the flanges 43, as best illustrated in Fig. 7.

Short angle iron sections 44 are secured to the plates 35 in spaced parallel relation above the angle iron 40, 41 and terminate spaced from the inner ends of the plates 35 and from the angles 37, 38 with which latter angles they are aligned as illustrated in Fig. 1. Pivoted to the studs 45 are short members 46 preferably of T-section and having inwardly projecting flanges 47. The members 46 are of a length to span the space between the angle irons 37 and 44 and are tapered at their free ends to bear against the angle irons 39, thereby forming a continuation of the track defined by the flanges 38 of the angle irons 37.

An elongated rigid arm 50 is pivoted to each plate 35 adjacent the junction between the angle irons 39 and 40 by means of studs 51. The forward or outer ends of these arms mount counterweights 52. The inner ends of these arms mount track sections 53 which in their normal position are aligned with the ends of the guide flanges of the angle irons 44 to form a continuation of the track. The arms 50 each mount a longitudinally projecting tongue 54. Brackets 55 to which the inner ends of the plates 35 are welded or otherwise secured, and which in turn are secured to the frame members 12 of the cement block machine, each have a bellcrank latching member pivoted thereto at 56. One arm 51 of the bellcrank normally is downwardly pressed by a spring 58 carried by the bracket 55 and bearing against arm 57. The downward movement of the arm 57 is limited by a stop bolt 59. The other arm 60 of the bellcrank extends downwardly below the pivot pin 56 and is notched at 61 to engage the forwardly projecting tongue 54 carried by the arm 50. The lower end of the arm 61 has a beveled nose portion 62 permitting the tongue 54 to latch itself automatically when swung in an upward direction from the dotted line position shown in Fig. 3. The parts are so proportioned and balanced that the weight 52 will normally urge the arm 50 to the full line position shown in Fig. 3, where the tongue 54 thereof may be latched by the latching bellcrank at 60, 61.

A feed member 31 is adapted to traverse the guide member described above and includes an end structure 65 positioned between the two opposite side guides 20 and provided at its opposite ends with vertical wall portions 66. The lower ends of the wall members 66 at both sides thereof mount projecting studs which journal rear rollers 67 and front rollers 68 adapted in their normal position to roll in the track provided by the guides between the flanges 38 of the angle irons 37 and the upper flanges 42 of the side plates 35. The end walls 66 project upwardly and provide brackets mounting studs or pins 69 spaced above the plate 65. The front rollers 68 are mounted upon the ends of a cross-shaft 70, and to this cross-shaft is pivoted, by means of bearings 71, a front carriage structure which includes side members 72, an inner cross-member 73, a plurality of spaced longitudinal supports 74, and a rear cross-member 75 mounting the bearings 71. Intermediate the length of this front carriage structure at a point substantially central of the side members 72, a pair of rollers 76 are journaled upon studs projecting from opposite side members 72 in axial alignment and adapted to traverse the guide unit mentioned above. The carriage is shiftable be-

tween two positions illustrated respectively in Figs. 1 and 3. In the Fig. 1 position, all of the rollers 76, 68 and 67 are supported upon the inwardly projecting flanges 38 of the angle irons 37 and are confined against upward movement by the flanges 42 of the plates 35. In this Fig. 1 position it will be observed that the pivoted front structure of the feed member, including the parts 72 to 75 inclusive, is positioned below the pallet supporting structure 25-30. The Fig. 3 position illustrates the opposite extreme of the movement and will be described hereinafter.

Each of the flanges 42 of the side plates 35 mounts a supporting block 80 for a bearing member 81 projecting above the level of the guide flange 43. A shaft 82 is journaled in the bearings 81 and is positioned adjacent to and inwardly from the left-hand inclined angle iron 29 of the pallet stacking structure as viewed in Fig. 1. Crank arms 83 are fixedly secured to the outer projecting end portions of the shaft 82 and each has pivotally connected thereto at 84 one end of a link 85. The opposite ends of the links 85 are pivotally connected to the studs 69 of the feed carriage. The shaft 82 also mounts a pulley 86 which has a driving connection through a belt 87 with a pulley 88 mounted upon a shaft 89 projecting from a speed reducing unit 90. The speed reducing unit 90 is mounted upon a platform 91 supported by the uprights 27 and by any other suitable bracing and supporting means carried by the stationary structure of the device in a position spaced laterally outwardly from the pallet stacking means, as illustrated in Fig. 5. The speed reducing means 90 includes an input shaft 92 which mounts a pulley 93 around which is trained another belt illustrated diagrammatically by the center line 94. This belt is trained on a pulley 95 mounted on the shaft of a motor 96 supported on a standard or base 97 fixedly secured upon the frame member 13 of the machine. It will be apparent that as the drive motor 96 operates, the pulley 86 is driven in predetermined timed relation and caused to rotate the shaft 82 and the cranks 83 so that connecting rods 85 are caused by their connections at 69 with the feed member to move the feed member along the guide between the position illustrated in Fig. 1 and the position illustrated in Fig. 3.

A plate 100 is secured to the rigid structure of the device and extends between the guide 20 and the bottom cross-member 25 of the stacking means, as best seen in Fig. 1. This plate mounts a pair of switches 101 and 102 provided, respectively, with spring-urged actuating arms 103 and 104 projecting therefrom. The shaft 82 mounts a disk 105 which is provided with two or more arcuate slots 106. Securing members 107 are adjustably positioned in the slots 106 and serve to secure in desired position upon the disk 105 a pair of blocks 108 and 109, each of which terminates adjacent to the periphery of the disk 105 and is provided with a projection 110 extending outwardly beyond the periphery of the disk 105. The blocks 108 and 109 are so arranged that the projections 110 thereof will strike the ends of the arms 103 and 104 of the switches 101 and 102 incident to rotation thereof. In the preferred embodiment of the invention the projection 110 of the block 108 will strike the arm 103 of the switch 101 once during each revolution thereof and will pass clear of the arm 104 of the switch 102. Likewise the

projection 110 of the block 109 will engage one arm 104 of the switch 102 and will pass clear of the arm 103 of the switch 101. The two switches 101 and 102 are connected in an electrical circuit (not shown) for the purpose of controlling the motor 96 in the proper sequence of operation of the device, said circuit preferably including a manually operated switch (not shown) for initiating the operation of the motor 96 in each cycle, and, if desired, the switches 101 and 102 may control other elements of the device or of the concrete block machine.

The front pivoted portion of the carriage of the feed member 31 has a cross-member 115 pivoted thereto by means of studs 116. The upper end of the member 115 projects above the level of the members 72, 73 and 74 whereby it is adapted to engage behind the lowermost pallet 11 in the stacking device when the parts are in the position shown in Fig. 1. The member 115 is positioned against a flange of the member 75 to prevent clockwise rotation thereof when in upright position. A projection 117 extends downwardly and is offset from the pivot axis of the studs 116, permitting counter-clockwise rotation of the member 115 limited by the member 75. In this counter-clockwise tilted position, the member 117 projects downwardly to engage the left-hand cross-bar 24 of the guide structure 20 as it approaches the position illustrated in Fig. 1, whereby when the feed carriage reaches the end of its stroke, illustrated in Fig. 1, it will be moved in clockwise direction to upright position. In other words, as the carriage moves toward its Fig. 1 position with the member 115 engaging the bottom side of the lowermost pallet 11 of the stack, that pallet will tilt the member 115 to permit it to pass under the pallet until the member 115 passes clear of the pallet to a position at the right of the pallet, as shown in Fig. 1, whereupon the member 24 swings the member 115 to its upright projecting position. Therefore, it will be observed that the members 115 serve as the means for withdrawing the lowermost pallet 11 from the stacking structure 25-30 during the working stroke without disturbing the pallets stacked in the device during the return stroke. The termination of the left-hand angle irons 29 of the stacking means above the bottom pallet permits the member 115, positioned upright by the member 75, to slide the bottom pallet only from the stack incident to the next forward movement of the carriage.

As the carriage is moved from the Fig. 1 to the Fig. 2 position by the cranks 83 and links 85, the pallet 11 is carried thereby in the general plane of the guide until it approaches the end of its stroke. At that point the rollers 76 at the front pivoted part of the carriage will run upon the track portions 53 of the guide which are carried by the counter-weighted arms 50 and will strike the bellcrank arms 60, swinging the same against the action of the spring 58 to disengage the tongues 54 mounted upon the arms 50. The weight of the carriage and the leverage exerted thereby is sufficient to overcome the counter-weight 52, whereupon the arms 50 swing about their pivot axes 51 to the dotted line position shown in Fig. 3. As the arms 50 swing to the dotted line position, the front portion 72-75 of the carriage pivots about the shaft 70 in a downward direction, tilting downwardly to the pallet-releasing position illustrated in Fig. 1. The angle of tilt in this instance is sufficient to permit the 75 pallet 11 to slide from the tilted carriage 72-75,

and the position of the front of the carriage is such that as the pallet slides therefrom, it will enter the mold 10 of the block machine. The rollers 76 thereupon engage the flange 41 of the lower angle iron 40, and, upon the return stroke of the carriage, the rollers 67, 68 will traverse the guide flanges 38 and 47 while the rollers 76 traverse the guide flanges of the angle irons 40 and 39. As the rollers 76 roll up the guide flanges of the angle iron 39, they will engage and upwardly pivot the T-sections 46, 47 of the track to permit the rollers 76 to ride upon the flanges 38 of the angle iron 37. As soon as the rollers 76 are clear of the tilted track sections 46, 47, the same lower by gravity to their normal position aligned with the flanges of the tracks 37, 44. The return of the front pallet-engaging portion of the carriage is thus in a path spaced below the pallets carried by the structure until the carriage is substantially at the commencement of its stroke and resistance to free movement of the carriage is minimized and the working load upon the machine is therefore reduced.

The swinging of the arms 50 from the full line to the dotted line position in Fig. 3 is limited by brackets 120 which are fixedly secured to the guides 20 and are provided with stop bolts 121 which may be adjusted in the brackets and which are engaged by the arms 50 in the dotted line position.

While the preferred embodiment of the invention has been illustrated and described herein, it will be understood that changes in the construction may be made within the scope of the appended claims without departing from the spirit of the invention.

I claim:

1. Pallet feed mechanism, comprising a stack support upon which a plurality of pallets may be stacked, a guide positioned below said stack support and extending laterally therefrom, a carriage shiftable on said guide to remove the lowermost pallet from said support, said carriage including a pivoted pallet-engaging section, said guide including an upper track portion and a lower track portion joining said upper track portion intermediate the ends of the latter, driving means for reciprocably shifting said carriage along said guide, said carriage traveling along said upper track during its feeding stroke to a discharge position at which the pivoted section thereof passes clear of said upper track and pivots to a pallet-releasing tilted position engaging said lower track to be guided by said lower track on its return stroke in a lowered position clear of said pallets for the major portion of said return stroke.

2. The construction defined in claim 1, wherein said upper track includes a pivoted section located at the junction of the upper and lower tracks, said pivoted track section being normally positioned by gravity in alignment with said upper track and being elevated by said pivoted carriage section to accommodate return of the latter from the lower track to the upper track during its return stroke.

3. The construction defined in claim 1, and a pivoted member carried by said guide and including a portion forming a continuation of said upper track, said member pivoting under the weight of said pivoted carriage section to tilt the latter and transfer it to said lower track.

4. The construction defined in claim 1, wherein said upper track includes a separate terminal portion, a pivoted member mounts said terminal

portion for bodily vertical movement, and a latch normally locks said pivoted member against movement, said carrier engaging and releasing said latch at a predetermined discharge position.

5. The construction defined in claim 1, wherein said carriage includes a plurality of rollers traversing said guide, said pivoted carriage section being supported by one of said rollers spaced from its pivot connection with the remainder of said carriage.

6. The construction defined in claim 1, wherein the pivoted section of said carriage mounts a projecting pallet abutment pivoted thereon for movement between predetermined limits, said abutment being pivoted to a retracted position upon engagement with a pallet during its return stroke, and an abutment on said guide engaged by said first abutment to pivot the latter to operative position at the conclusion of said return stroke.

7. The construction defined in claim 1, wherein a member is pivoted to said guide on a horizontal transverse axis, said pivoted member mounting a terminal section of said upper track, and a counterweight carried by said pivoted member to normally hold said terminal track portion in operative position, said carriage overbalancing said counterweight when the weight thereof is applied to said terminal section.

8. The construction defined in claim 1, wherein a member is pivoted to said guide on a horizontal transverse axis, said pivoted member mounting a terminal section of said upper track, a counterweight carried by said pivoted member to normally hold said terminal track portion in operative position, said carriage overbalancing said counterweight when the weight thereof is applied to said terminal section, and a stop on said guide limiting lowering movement of said member.

9. The construction defined in claim 1, wherein a member is pivoted to said guide on a horizontal transverse axis, said pivoted member mounting a terminal section of said upper track, a counterweight carried by said pivoted member to normally hold said terminal track portion in operative position, said carriage overbalancing said counterweight when the weight thereof is applied to said terminal section, and a latch on said guide normally locking said member in operative position and releasable by engagement of said carriage therewith.

10. The construction defined in claim 1, wherein said driving means comprises a power driven actuator, a crank rotated by said actuator, and a link connecting said crank and said carriage.

11. The construction defined in claim 1, wherein said driving means comprises an electrical motor, a crank driven by said motor and a link connecting said crank and carriage, an electrical switch having an actuator juxtaposed to said crank, and an abutment carried by said crank and engageable with said switch actuator.

12. A pallet feeding device comprising a support, a rack carried by said support and adapted to carry a stack of pallets, a guide carried by said support below said rack to project laterally therefrom, a carriage shiftable on said guide, upper and lower tracks carried by said guide, driving means for reciprocating said carriage longitudinally of said guide, a terminal portion of said upper track being bodily shiftable when engaged by said carriage during its feed stroke to tilt said carriage to pallet-releasing position and transfer a portion of said carriage to said lower track,

said lower track joining said upper track to return the carriage to said upper track in engagement with said stack at the end of its return stroke.

13. A pallet feeding device comprising a support, a rack carried by said support and adapted to carry a stack of pallets, a guide carried by said support below said rack to project laterally therefrom, a carriage shiftable on said guide, upper and lower tracks carried by said guides, driving means for reciprocating said carriage longitudinally of said guide, a terminal portion of said upper track being bodily shiftable when engaged by said carriage during its feed stroke to tilt said carriage to a pallet-releasing position and transfer a portion of said carriage to said lower track, said lower track joining said upper track to return the carriage to said upper track in engagement with said stack at the end of its return stroke, and a latch normally locking the terminal track portion in operative relation to said upper track, said carriage releasing said latch at the end of its feed stroke.

14. A pallet feeding device comprising a support, a rack carried by said support and adapted to carry a stack of pallets, a guide carried by

5
15
10
20
25

said support below said rack to project laterally therefrom, a carriage shiftable on said guide, said carriage including two pivotally connected sections, driving means connected with one carriage section for reciprocating said carriage on said guide, the other carriage section being adapted to engage and propel therewith the lowermost pallet from said stack during the feed stroke of said carriage, means for tilting the pallet propelling section of said carriage to discharge position at the end of its feed stroke, said guide positioning said pallet engaging section of said carriage spaced below said stack during the major portion of the return stroke of said carriage.
